ELECTRIC PLUG

Nathan Chirelstein, Chicago, Ill.

Application August 11, 1937, Serial No. 158,542

2 Claims. (Cl. 173—361)

My invention relates to electric plug constructions. The object of my invention is to provide an improved male plug portion of a plug and socket combination, which may be easily coupled with the female member in which the sockets are formed, and which may be easily removed therefrom without danger of becoming permanently locked in coupled relation.

A further object is to provide a blade construction of sheet metal that will be flexible, and strong enough to maintain its form from permanent distortion when subjected to stress in the act of coupling and uncoupling the plug from the female or socket member of the plug construction.

In the Patent No. 2,037,562 dated April 14, 1936, granted to me, I have disclosed a construction in which a thin blade is used to provide resiliency, which is formed by folding the blades at their free ends to provide branch portions which serve to effect good contact with the terminal members of the female portion of a plug.

In said patent an opening is formed in the branch adjacent its point of junction with the blade, which serves to weaken the stiffness of the branch and cause it to bend and thus provide a shoulder such as illustrated in Fig. 1 of the patent.

The location of the shoulder adjacent the free end of the branch, permits of more or less relative movement between the female member and plug member when the plug member is coupled with a female member that is formed with inner walls such as 13—illustrated in the present application.

The standard thickness of a blade is one-sixteenth of an inch and the width of the slot of the female member varies between three and four-thirty-secs of an inch, thus allowing in many cases but one-thirty-second of an inch for clearance.

The offset portion of the blade between its point of junction and the adjacent end of the opening, increases the thickness of the blade as a whole at this point, and due to its width and stiffness it is sometimes difficult to remove it from the socket when the socket opening is of minimum width.

In the present construction the blades are made of resilient metal, each blade portion having a thickness of about one-thirty-second of an inch and about one-quarter of an inch in width, and made from a strip which is bent back upon itself the full length of the blade to form a blade of two layers, one or both of which may have

a branch portion extending outwardly therefrom, and formed integral therewith at a point near its free end.

Each branch portion is formed integral with the blade and struck out from its middle part and is therefore of less width and length than that of the blade, and by reason of its reduced width and thickness will yield easily under pressure in the act of coupling or uncoupling the plug from the socket member.

Referring to the drawing which forms a part of the present specification:

Fig. 1 is a vertical sectional view of a plug construction in which the plug portion is shown with its blades partly inserted in the sockets of the female portion, and illustrates the action of the blades in passing thru the slots formed in the face of the socket portion.

Fig. 2 is a vertical sectional view of the plug and a part of the socket portion as they appear in coupled relation.

Fig. 3 is a view of the face end of the plug.

Fig. 4 is a perspective view of a blade member constructed as illustrated in Fig. 1.

Fig. 5 is an elevational view of a blade member formed to provide a space or slot at each side of the branch member to insure freedom of movement of the branch when pressed thru the opening formed in the stem of the blade.

Fig. 6 is a perspective view of a blade formed with two branch portions.

Fig. 7 is a perspective view of a blade construction, the branch of which is formed without a shoulder near its free end, one half of the blade remaining imperforate opposite the opening made in the opposite side in forming the branch.

Fig. 8 is a vertical sectional view showing the blade illustrated in Fig. 7 located in a portion of a socket member of a plug, and illustrating the curvature of the branch portion when inserted in a socket member formed with a wall such as 13 of the drawing.

10 indicates the body of the plug, and 11 the socket portion of a plug now in general use.

The socket portion is formed with a rim 12 hereinafter referred to as the face of the plug, and is formed with an inner abutment plane surface 13 for each blade, the wall 14 formed there-between being about one-eighth of an inch in thickness and having slots 15—15 respectively formed therein; the drawing showing the construction on an enlarged scale.

16—16 respectively, indicate the terminal conductors of a standard socket construction.

The body of the plug 10 is made of insulating 55

material and formed to provide a central passage 17, and an inner plane surface 18, in which recesses 19—19 respectively are formed to receive the screws 20.

5 The blades 21—21 respectively are each provided with a flat base portion 22 and the blades extend at an angle thereto as shown at 23 and each blade being bent back upon itself at its outer free end 24, and bent to form an extension 25 thru which a screw 20 extends to secure them to the body portion 10.

The extension 25 stiffens and strengthens the base portion of the blade and prevents it from being easily bent under strain in the act of removing the plug from the socket member.

In all of the figures except Fig. 6, I have shown a branch 26 struck out from a blade 21 from one side strip only.

In Fig. 6 I show a branch struck out from both 20 side strips forming the blade proper intermediate its edges.

This construction insures good contact with the blade of the socket member regardless of which side thereof contacts the blade of the plug member, and yields easily in the act of removal from the socket, and yet holds firmly in the socket under normal operating conditions.

If desired, the shoulders 31 may be dispensed with and the branch or branches formed as illustrated in Fig. 7 for use with socket members that have no inner wall such as 13, but where a shoulder is formed on a branch I prefer to provide an opening 32 to allow the end of the branch to extend therethru in the act of coupling and uncoupling the body portions.

I prefer to make the branches somewhat wider at their points of junction with the blades and therefore provide a stiffening effect which gradually becomes less toward the end 29 which extends to nearly the face of the female member when the body portions of the plug are coupled, the free end resting in the slot as shown in Figures 2 and 8.

Each branch shown in Figures 1 to 6, inclusive, 45 is bent near its free end and extends inwardly toward the blade as shown at 31, and the opposite member 21' is formed with an aperture 32 into which the free end of the branch may enter in the act of inserting or removing the plug from the sockets.

This construction permits a greater movement of the branch inwardly and is sufficient to prevent the blade from jambing in the slot when it is very narrow in width.

55 A further improvement is that of forming a slot or space 33 at each side of the branch to prevent contact of the adjacent edges of the wall of the blade in case the branch becomes slightly bent in use, such bending causing the branch to 60 wedge in the slot of the stem and preventing the withdrawal of the blades from the sockets.

In the construction shown in Figure 6, I prefer to make one of the branches a little shorter than the other to allow one free end to overlap the adjacent end of the other branch and provide for a greater degree of movement toward each other in the act of coupling or uncoupling the body portions.

As illustrated in Figure 1, in the coupling operation the ends of the branches may pass entirely thru the blades, thus permitting a relatively greater offset shoulder 31 to be formed in the branches without danger of jamming in the slots.

As thus constructed the plug may be used without fear of the blades becoming bent or twisted when in use for the reason that the two part blade extends from its free end to its base-plate and is secured thereto, thereby preventing the blade from bending out of shape in the act of pulling it from the socket, or from being easily bent in handling.

Having thus described my invention I claim as new:

1. An attachment plug comprising a body portion of insulating material having a flat face and a pair of flat contact blades extending outwardly of the flat face and spaced apart a distance corresponding to the separation between the socket openings of a standard receptacle, each of said blades being formed from a strip of thin resilient metal bent upon itself to provide a blade of two layers, one of said layers being formed with an aperture and the other layer having a branch struck therefrom intermediate its side edges and projecting outwardly from said layer, said branch having an offset shoulder adjacent its free end, said branch extending from adjacent the free end of the blade and the free end of the branch being spaced from the flat face of said body portion with the shoulder at the free end of the branch movable to enter the blade layer aperture during the attachment of the plug to a standard receptacle.

2. An attachment plug comprising a body portion of insulating material having a flat face and a pair of flat contact blades extending outwardly of the face, each blade being made from a strip of thin resilient metal folded upon itself to provide two layers in contact with each other throughout their lengths, each of said layers being provided with a branch struck therefrom intermediate the side edges thereof and offset therefrom, the branches extending from adjacent the free ends of the blade, the free ends of the branches being spaced from and terminating adjacent the flat face of said body portion and a shoulder adjacent the free end of each branch normally offset from the adjacent side of the blade.
